Primary Examiner — Karen S Acker*(74) Attorney, Agent, or Firm* — Amster, Rothstein & Ebenstein LLP(57) **CLAIM**

The ornamental design for a paper product with surface pattern, as shown and described.

DESCRIPTION

FIG. 1 is a perspective view of a paper product with surface pattern;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a back view thereof.

The broken lines surrounding the drawings depict the boundaries of the claim and form no part thereof.

1 Claim, 5 Drawing Sheets(56)
